UNITED STATES PATENT OFFICE.

EDWARD CURRAN SMITH, OF SCHENECTADY, NEW YORK.

MUCILAGE-BRUSH.

SPECIFICATION forming part of Letters Patent No. 580,013, dated April 6, 1897.

Application filed July 7, 1896. Serial No. 598,279. (No model.)

To all whom it may concern:

Be it known that I, EDWARD CURRAN SMITH, a citizen of the United States, and a resident of Schenectady, county of Schenectady, and State of New York, have invented certain new and useful Improvements in Mucilage-Brushes, of which the following is a specification, reference being had to the accompanying drawings, forming a part thereof, in which similar letters of reference indicate corresponding parts.

This invention relates to an improvement in brushes of the class especially adapted for use as mucilage-brushes, the object of the invention being to provide an article of this character which is so constructed as to normally maintain the brush portion thereof out of contact with the mucilage or other fluid matter used therewith, whereby the brush will not clog and the neck of a bottle or other receptacle adapted for use in combination with the brush can be kept in a clean condition.

The invention will be hereinafter fully described, and specifically set forth in the annexed claims.

In the accompanying drawings, forming part of this specification, Figure 1 is a perspective view of my improved mucilage-brush, illustrating the operation thereof; and Fig. 2 is a vertical sectional elevation of the brush, illustrating the same in engagement with the neck of a mucilage-bottle.

In the practice of my invention I provide a cylinder of metal or other suitable material A. Within the lower end of this cylinder is secured a cylindrical box B, which said box has a solid head b upon the upper end thereof and which is open at its lower end.

Engaging with the box B is a head or plunger C, which has a brush D attached thereto. This said brush when contracted fills the entire area of the box B, as illustrated in Fig. 2 of the drawings, but when it is released from the said box its bristles will expand approximately, as shown in Fig. 1 of the drawings.

Telescoping with the upper end of the cylinder A is a cylinder A', which has a closed head thereon, from which head is projected a rod E, which is secured at its lower end to the sliding head C of the brush D, and to maintain the brush D in its closed position, as

illustrated in Fig. 2 of the drawings, a normally-expanded spiral spring F is provided, which said spring occupies the entire vertical space between the head b of the box B and the head a of the cylindrical section A', whereby said section will be normally maintained in an upward position. 55

As a means for engaging the inner edge of the neck of the bottle G the cylinder A is provided with a spherical stopper A², which said stopper is adapted for engagement with bottles of various sizes. Said stopper is also adapted for vertical adjustment upon the cylinder A, whereby the end of said cylinder can be extended into bottles for any desired depth. 60

In the operation of the device the end of the cylinder will be normally maintained above 70 the level of the mucilage contained in the bottle, and when it is desired to extract mucilage therefrom the cylindrical section A' will be pressed downwardly, whereby the brush D will be forced into the mucilage, which can 75 then be applied to any suitable surface adapted to be mucilated.

When pressure is released from the head a of the cylinder A', the brush will be carried back automatically into the box B, and any 80 surplus mucilage contained in the brush will be scraped off upon the edge of the box and dropped back into the bottle by the act of compressing the bristles forming the brush.

I have described my invention as being specifically adapted for use as a mucilage-brush, but it is obvious that under the scope of my invention I am not confined to any special application of the device. It is obvious that I am entitled to slight variations in the mere 90 mechanical details of constructing the device. 85

Having thus described my invention, what I claim as new, and desire to secure by Letters Patent, is—

1. A brush comprising a telescopic cylinder 95 having its outer section normally maintained in an upward position by means of a spring-pressed rod, said rod engaging with the brush-head, which head and brush engage with a box rigidly located within the lower end of 100 the telescopic cylinder, substantially as shown and described.

2. The combination of a cylinder having a box in its lower end with a head thereon and

a rod which passes through said head and has a brush attached to its lower end and a sliding cylinder attached to its upper end, the two said parts being normally pressed apart by means of a spiral spring surrounding the said rod, the said cylinder being supplied with a stopper or collar for engagement with a bottle, substantially as shown and described.

In testimony that I claim the foregoing as my invention I have signed my name, in presence of two witnesses, this 2d day of July, 1896.

EDWARD CURRAN SMITH.
